HAT

Inez W. Sahlin, Van Nuys, Calif.

Application December 22, 1952, Serial No. 22,805

Term of patent 3½ years

(Cl. D3—13)

To all whom it may concern:

Be it known that I, Inez W. Sahlin, a citizen of Sweden, residing at Van Nuys, State of California, have invented a new, original, and ornamental Design for a Hat, of which the following is a specification, reference being had to the accompanying drawing, forming a part hereof.

Fig. 1 is a side perspective view of a hat showing my new design.

Fig. 2 is a front perspective view of the hat shown in Fig. 1.

Fig. 3 is a side elevational view, and

Fig. 4 is a front elevational view thereof.

I claim:

The ornamental design for a hat, as shown.
